UNITED STATES PATENT OFFICE.

GEORGE M. HUBBARD, OF NEW HAVEN, CONNECTICUT, ASSIGNOR TO O. B. NORTH & CO., OF SAME PLACE.

GAG-RUNNER.

SPECIFICATION forming part of Letters Patent No. 278,554, dated May 29, 1883.

Application filed March 12, 1883. (No model.)

To all whom it may concern:

Be it known that I, GEORGE M. HUBBARD, of New Haven, in the county of New Haven and State of Connecticut, have invented a new Improvement in Gag-Runners; and I do hereby declare the following, when taken in connection with accompanying drawings and the letters of reference marked thereon, to be a full, clear, and exact description of the same, and which said drawings constitute part of this specification, and represent, in—

Figure 1, a perspective view of the runner detached; Fig. 2, a perspective view of the loop; Fig. 3, a sectional view; Fig. 4, a perspective view, showing the parts as arranged upon a strap.

This invention relates to an improvement in the article of harness-hardware commonly called "gag-runner"—that is, the loop attached to the bridle through which the check-rein passes—the object of the invention being to make a runner which will be of easy adjustment; and it consists in the construction as hereinafter described, and more particularly re-cited in the claim.

The runner A is of substantially the usual shape; but preferably the two ends *a b* are disconnected and separate the one from the other, as seen in Fig. 1. The end *b* is provided with a stud, *d*, upon its back, the other, *a*, with a shoulder, *e*, upon its front a little distance from the end, and inclined from that shoulder to the point. When the runner is thus divided at its upper end, the metal should possess a certain amount of elasticity, so that the two ends may be brought nearly together and react to assume their normal or open position.

B is a loop, its opening corresponding substantially to the strap or straps upon which the runner is to be placed. In the outside bar is a notch, *f*, corresponding to the width of the end *a* of the runner. The loop *B* is first placed upon the strap *C*, as seen in Fig. 3, a little

above where the loop is to be fixed. The runner is then set upon the strap, the stud *d* into the proper hole in the strap to give the required position for the runner. Then the loop *B* is forced down over the ends of the runner below the shoulder *e*, the ends of the runner closing for this passage of the loop, and then the elasticity causing the reaction brings the shoulder *e* over the loop, and thus the parts are firmly held together. At any time when it is desirable to readjust the runner, press the two ends together until the loop can be passed up onto the strap away from the runner, and then withdraw the runner from its hole in the strap and set it to the required position and replace the loop.

I do not wish to be understood as claiming, broadly, a gag-runner constructed at one end with a stud to enter a hole in the strap, combined with a loop around the strap, and arranged to pass over the stud end of the runner, and there engage a shoulder for the purpose of holding the runner to the strap, as I am not the inventor of such a runner, my invention being for the divided or separated ends of the runner, whereby the stud is attached to one part, and the other part, formed with a shoulder, acts as a latch to engage with the securing-latch.

I claim—

The herein-described gag-runner, having its two ends *a b* separated, the one side constructed with a stud, *d*, to enter the hole in the strap, the other with a shoulder, *e*, combined with a loop arranged to pass over the strap and be returned onto the runner over the shoulder *e*, to embrace the ends of the runner and the strap, substantially as described.

GEORGE M. HUBBARD.
